UNITED STATES PATENT OFFICE.

CHARLES AUGUSTUS DE RIGNE, OF LOS ANGELES, CALIFORNIA.

PUMP PLUNGER.

Application filed June 12, 1922. Serial No. 567,645.

To all whom it may concern:

Be it known that I, CHARLES AUGUSTUS DE RIGNE, a citizen of the United States, residing at Los Angeles, in the county of Los Angeles and State of California, have invented certain new and useful Improvements in Pump Plungers; and I do declare the following to be a full, clear, and exact description of the invention, such as will enable others skilled in the art to which it appertains to make and use the same.

This invention relates to an improved plunger which is especially designed for use in pneumatic pumps of the class used for inflating vehicle tires and the like.

The principal object of the invention is to generally improve upon plungers of this class by providing one, embodying a head of novel construction, the same being composed of comparatively few and inexpensive parts which are capable of rapid separation in order to make the repairs and replacements whenever necessary.

More specifically speaking, it is one of the objects of the invention to provide a plunger head which has a removable sleeve on its lower end formed with a groove with which the hooked free ends of the radial arms of a spring abutment are engaged.

Other objects and advantages of the invention will be apparent during the course of the following description.

In the accompanying drawings forming a part of this specification and in which like numerals are employed to designate like parts throughout the same;

Figure 1 is a side elevational view of the conventional form of a pneumatic pump with a portion of the cylinder broken away so as to disclose the improved plunger head.

Figure 2 is an enlarged central vertical sectional view through the head showing the details and construction more clearly.

Figure 3 is a transverse section taken on line 3—3 of Figure 2.

In the drawings, the letter B designates an air pump barrel or cylinder having a base A at its lower end with a valved flexible conduit C leading from the usual passage in the base which has communication with the cylinder. Slidable in the cylinder is the plunger, comprising a rod R having a head H on its lower end and a handle G on its upper end.

As before intimated, the invention resides in the construction of the head H. By di-

recting attention to Figure 2, the preferred construction of the head can be clearly seen. As here shown, it has detachable threaded connection with the lower end of the rod and that portion adjacent the connection is formed with the plurality of openings 1 having communication with the upper chamber in the cylinder. Adjacent this apertured partition 2 and below this partition it is formed with a reduced externally screw-threaded part 3 in which a check valve 4 is arranged. This valve cooperates with the central port in the partition 2 and a coiled spring 5 serves to maintain it closed. As before suggested, it is desirable to provide a novel anchor or abutment which is to be associated with the lower end of the coiled spring. This abutment is generally indicated by the numeral 6 and, in its preferred form, comprises a cup 7 in which the lower end of the spring received and a plurality of radial arms 8 which have their outer ends bent to form hooks 9 designed for a reception in a circumferential groove 10 formed at the bottom of the sleeve 11 which is threaded onto the reduced portion of the body as shown. It is to be noted that by reducing the lower portion of the body as described, a shoulder 12 is formed and packing members 13 are arranged on the reduced part 3 above the upper end of the aforesaid sleeve, said packing members being tightly clamped against the shoulder by means of a nut 14 which is arranged on the reduced portion of the body.

In operation, it will be seen that air chambers will be formed above and below the plunger head and the air will be alternately compressed in the chambers according to the direction of the movement of the piston. On the upward stroke, the air in the upper chamber will force its way through the openings 1 and through the central port in the partition 2 and press against the valve 4 to open it against the action of the coil spring 5, thus permitting the air to pass downwardly through the hollow reduced part 3 of the body. The air will then find its way through the spaces between the radial arms 10 of the spring abutment and will be forced outwardly through the aforesaid valved flexible conduit C.

From the foregoing description it is manifest that I have devised an extremely novel and practical plunger which is unique, simple in construction, and such as to per-

mit the packing members, or any other details which may need to be repaired, to be easily and readily replaced. The construction is such as to insure effectiveness 5 of operation and to render the plunger inexpensive to both the manufacturer and the user. Other features and advantages have also been made clear from the foregoing description. Consequently, by carefully considering the description in connection with 10 the drawings, persons familiar with devices of this class will doubtless be able to obtain an understanding of the invention. Therefore, a more lengthy and detailed description 15 is deemed unnecessary.

Since probably the best results may be obtained with the construction and arrangement herein shown and described, this is taken as the preferred embodiment of the 20 invention. However, I wish it to be understood that minor changes coming within the scope of the invention as claimed may be resorted to if desired.

I claim:—

25 1. A pump plunger comprising a hollow body open at its lower end and having an internal valve seat and side openings above the valve seat, a sleeve carried by the lower portion of said body and having an annular 30 seat adjacent its lower end, a valve element in the hollow body beneath the valve seat, a spring beneath said valve, and a spring support engaging the lower end of said spring and having mounting means fitting into the 35 annular seat to retain the spring support in place.

2. A pump plunger having a head on its lower end including a body having valved

air passage, being formed at its lower end with a circumferential groove, and a spring 40 abutment or anchor formed with a central cup for a reception of one end of the valve spring and a plurality of radial arms equipped at their outer ends with hooks to engage in said groove. 45

3. A pump plunger having a head on its lower end including a body having an air passage, said head having its lower end portion provided with an annular seat, a valve for the air passage opening downwardly, a 50 spring carrier including mounting means fitting into said seat, and a spring positioned between the spring carrier and valve for yieldably holding the valve in a raised and closing position. 55

4. A pump plunger having a head on its lower end, said head comprising a body having valved passage for the air and a reduced externally screw threaded portion in which the valve is arranged, a sleeve engaged with the screw threaded portion of said body, said sleeve having a circumferential groove formed at its lower end, a valve, a spring for closing the valve, an abutment for the lower end of the spring 60 having a centrally disposed seat for reception of the lower end of the spring and supporting arms having hooks at their free ends engaged in said groove, and a packing associated with the head. 65

In testimony whereof I have hereunto set my hand.

CHARLES AUGUSTUS DE RIGNE.
